UNITED STATES PATENT OFFICE.

FRANK J. QUIST, OF WORCESTER, MASSACHUSETTS.

CARPET-CLEANER.

1,168,225.

Specification of Letters Patent.

Patented Jan. 11, 1916.

Application filed October 18, 1913. Serial No. 796,032.

To all whom it may concern:

Be it known that I, FRANK J. QUIST, a citizen of the United States, residing at Worcester, in the county of Worcester and 5 State of Massachusetts, have invented a new and useful Carpet-Cleaner, of which the following is a specification.

This invention relates to a carpet cleaning device and the principal objects thereof are 10 to provide a device of this character in a small and compact form, arrange the parts in such a way that they will operate easily and without undue friction, and especially to provide for separating the dust in such a 15 way as to leave the dust in an open-topped casing or frame so that it can be emptied expeditiously and in a cleanly way.

The invention has for one of its objects the doing away with the ordinary dust bag 20 which has to be handled in order to be emptied, and to substitute therefor a rigid casing which the operator can grasp at one end at a place where there is no dust, and in fact to provide an improved construction 25 in which there is no screen or dust separating device of any kind that has to be handled or can be handled independently of the nozzle.

Another object of the invention is to provide 30 an improved construction in which the part containing the suction creating devices is an entirely separate element from that containing the dust separating devices and can be handled, manufactured and repaired 35 separately.

Another object of the invention is to provide 40 a device of this character in which a rotary brush can be combined with the suction features of the cleaner in a simple manner and without adding greatly to the expense thereof, and to provide means for insuring that the dust is entirely separated 45 from the air before it is discharged from the machine.

Further objects and advantages of the 50 invention will appear hereinafter.

Reference is to be had to the accompanying drawings in which—

Figure 1 is a side view of a preferred 55 form of the invention; Fig. 2 is a sectional view on a central plane parallel with the sides shown in Fig. 1; Fig. 3 is a plan of part of the lower casing removed from the upper; Fig. 4 is a side view showing how the two parts are separated in practice, and Fig. 5 is a view similar to Fig. 2 showing a

modified form coming within the scope of the invention.

Referring to the first four figures, the device is shown in two parts A and B. Each 60 of these parts is shown in the form of a casing or frame. The upper part B is provided with any ordinary type of suction creating device such as a bellows 10 and with the usual operating wheels 11 on a 65 crank shaft 12 connected by links 13 or the like with the bellows for operating the same. These wheels are located at one end of the entire device and support that end. This part B is also provided with a handle 14 for 70 operating the machine.

The casing B is provided with a bottom wall 15 having ports 16 and 17. This bottom wall constitutes the bottom of the bellows and the port 16 is the inlet while the 75 port 17 is the exhaust port. It is provided with automatic spring valves 18 and 19 respectively which operate in an obvious manner.

The part A of the device is shown in the 80 form of a single casing which in these figures is provided with a nozzle 20 at one end for supporting that end of the machine. This nozzle has a passage 21 extending upwardly therefrom and separated from the 85 front chamber 22 by a wall 23 which does not extend quite to the top of the casing or chamber.

It will be seen that when the parts are 90 assembled in a manner that will be described hereinafter, the operation of the bellows will cause air to be drawn into them through the port 16 from the nozzle. Any heavy 95 particles of dust and other substances that do not enter the bellows will be deposited in the bottom of the chamber 22 instead of remaining in the nozzle. This chamber is located out of the path of air from the nozzle to the bellows so that if any particles are left in it they will not be again disturbed by the air. No means is provided for 100 separating the dust before the current of air and dust passes into the bellows, and this current is unrestricted.

The dust laden air passes into the bellows 105 and out through the port 17 into a dust separating chamber 24 which is located between the chamber 22 and the wheels 11 and obviously also is located under the bellows. This chamber is entirely separated 110 from the chamber 22 by a middle wall 25 and is provided with an external wall,

shown in the drawings as a bottom one, formed of a screen device 26. This is made with depressions and elevations as indicated for the purpose of increasing the area 5 through which the air is forced out and for the further purpose of providing a passage for air after a considerable layer of dust is deposited in the lower portions. By discharging the air at the bottom near the 10 floor, any dust that might escape on account of the wearing of the parts will be deposited directly on the floor, where it can be taken up by the nozzle, instead of being forced out into the air of the room.

15 It will be obvious that the two chambers 22 and 24 are open at the top so that when the parts A and B are assembled they will communicate properly with their respective ports in the bottom of the bellows. The 20 bottom of the bellows is preferably provided with packing 27 in position to come into contact with all the vertical walls of the lower part A.

For the purpose of connecting the two 25 parts of the device together in a readily adjustable manner, one part, preferably the part B, is provided with a plate 30 having a headed stud 31 fixed thereon and provided with an integral stop 32. On this stud is 30 provided a circular plate 33 arranged eccentrically with respect to the stud and having retaining lugs 34, and an integral handle 35. This eccentric is provided with an eccentric strap 37 arranged under the retaining lugs and handle and carrying a hook 36. On the other part of the device is a spring clip 38 for receiving the hook. This is shown in the form of a curved wire secured to the casing A which is provided 40 with a clip 39 for holding the hook in position and permitting it to spring slightly as the eccentric part of the catch is operated.

In the form shown in Fig. 5, the parts 45 are the same with the exception of the nozzle and connected parts. The chamber 22^a is provided with a wide nozzle 20^a about at the center of the chamber and plates 23^a extend upwardly at the two sides of this wide 50 nozzle so as to form pockets beyond them in both directions. Within this nozzle is located a rotary brush 40 extending down below the bottom of the nozzle. This brush is provided with rolls 41 on the ends contacting with rubber covered rollers 42 which engage the floor and operate the rolls and brush. In this way any heavy particles that are thrown to one side by the brush are deposited on the two sides thereof out of the 55 air current before the air passes into the ports 16 and the remainder of the operation is the same as that heretofore described.

Although I have illustrated and described 60 only two forms of the invention I am aware of the fact that other modifications can be

made therein by any person skilled in the art without departing from the scope thereof as expressed in the claims, therefore I do not wish to be limited to the special forms shown, but

70 What I do claim is:—

1. In a carpet cleaner, the combination of a casing, supporting wheels at one end thereof, a nozzle for supporting the other end of said casing, means whereby the air 75 and dust from the nozzle are conducted directly into the casing, and a dust separating chamber located directly under the casing between the nozzle and wheels and receiving air and dust from the casing, said 80 chamber having a bottom filtering wall constituting the outlet thereof located near the plane of the bottoms of the wheels and nozzle.

2. In a carpet cleaner, the combination 85 of a casing, a nozzle at one end and supporting wheels at the other end, bellows in said casing connected with said wheels for operation thereby, a dust chamber located under the bellows between the nozzle and 90 wheels and having a screen constituting the bottom and the outlet thereof, said bellows having valves for the conduction of air to the bellows from the nozzle and to the dust chamber from the bellows.

95 3. In a carpet cleaner, the combination of two casings detachably connected together, one above the other, a bellows located in the upper casing, wheels connected with the upper casing for supporting one 100 end of the apparatus and connected with the bellows for operating it, the lower casing being open at the top and fitting the bottom of the upper casing and having a nozzle at the end opposite the wheels, a 105 dust separating chamber between the nozzle and wheels, and means whereby the air drawn in through the nozzle will be taken into the bellows and then forced out through the dust separating chamber.

110 4. In a carpet cleaner, the combination of two casings, an upper one and a lower one, operating wheels carried by one of the casings, the lower casing having a nozzle at the end opposite the wheels and provided with an open-topped dust separating chamber having an external filtering wall, and means whereby the rotation of said wheels will cause air to be drawn into the upper casing through said nozzle and forced out 115 through said dust separating chamber.

120 5. In a carpet cleaner, the combination of two casings, an upper one and a lower one, operating wheels carried by one end of the upper casing, the lower casing having a nozzle at the end opposite the wheels and provided with an open-topped dust separating chamber having an external filtering wall, means whereby the rotation of said 125 wheels will cause air to be drawn in to the 130

upper casing through said nozzle and forced out through said dust separating chamber, and means for detachably securing the lower casing to the upper casing.

6. In a carpet cleaner, the combination with an upper casing having a bottom wall provided with two ports, valves for said ports, a bellows within said casing communicating with said ports, and means carried by said upper casing for operating the bellows, of a lower casing having a nozzle, said nozzle communicating with said upper casing through one of said ports, a dust separating device communicating with the bellows through the other port, and having a screen constituting an external wall, and means for detachably connecting said casings together.

7. In a carpet cleaner, the combination with a casing, and a suction creating device carried thereby, of a casing adapted to be detachably connected with the bottom thereof, and having a nozzle at one extreme end, and a dust separating chamber separated from the nozzle, but arranged to receive air and dust from said suction-creating device, and provided with an external screen constituting one wall and the outlet thereof.

In testimony whereof I have hereunto set my hand, in the presence of two subscribing witnesses.

FRANK J. QUIST.
